J. J. MARCY, OF WEST MERIDEN, CONNECTICUT, ASSIGNOR TO HIMSELF AND E. MILLER AND COMPANY, OF SAME PLACE.

Letters Patent No. 89,491, dated April 27, 1869.

IMPROVEMENT IN MACHINE FOR SPINNING METAL.

The Schedule referred to in these Letters Patent and making part of the same.

To all whom it may concern:

Be it known that I, J. J. MARCY, of West Meriden, in the county of New Haven, and State of Connecticut, have invented a new Improvement in Machine for Spinning Metal; and I do hereby declare the following, when taken in connection with the accompanying drawings, and the letters of reference marked thereon, to be a full, clear, and exact description of the same, and which said drawings constitute part of this specification, and represent in—

Figure 1 a top view;

Figure 2, a front view; and in

Figure 3, a partial top view, to illustrate the operation of the machine.

This invention relates to an improvement in forming articles from sheet-metal, by the process commonly known as "spinning," the object being to positively guide the spinning-tool without connecting the tool with machinery which revolves the metal being formed; that is to say, the former and metal are caused to revolve together by power, while the tool is moved by hand, being guided by a positively-defined path.

To enable others skilled in the art to construct and use my improvement, I will fully describe the same, as illustrated in the accompanying drawings.

A is the bed of the machine, upon which the operative mechanism is supported.

B is the mandrel, revolving freely in bearings, C, and driven in the usual manner of similar mandrels, by the application of power thereto through the pulley C'.

On the said mandrel the former D is placed, here represented as a cone, but may be of any desired form to which it is desired to bring the metal.

E is a spindle, arranged in a head, E', and in a line axially to the mandrel B, so as to be moved toward or from the said mandrel, by means of the scroll-wheel, or cam E⁵, the said wheel having a spiral groove upon its under surface, and a stud on the mandrel entering the said groove, as seen in fig. 2, so that by turning the said wheel, the mandrel is quickly forced forward or drawn back, and the bearing of the stud on the wheel being in a line radial from the centre of the wheel is held firmly by the said groove without any other security, the said spiral groove being indicated by broken lines in fig. 1.

Upon its inner end is fixed a sleeve, a, (see fig. 3,) which revolves freely on the said spindle, without causing the revolution of the said spindle.

The disk of metal to be formed is placed upon the end of the former, and clamped thereon, by forcing the spindle E toward the mandrel, to press the sleeve against the disk, as seen in fig. 3, the disk being denoted in red, so that when the mandrel and former revolve, the disk being firmly held, will revolve with the mandrel.

Thus far the device is common, and the usual manner of bringing the disk down on to the former has been by the use of a spinning-tool, in the hand of the operator, working the metal down by degrees until the desired form is attained.

To facilitate this operation I arrange a carriage, G, on a guide, H, of the bed-plate, to which a longitudinal movement is imparted by a cam, H¹, on the transverse shaft, H², the said cam being connected to the carriage by a rod, I, threaded, so that by the turning of the nuts w w, the carriage G, on the slide L, may be adjusted longitudinally relative to the block P, so that the tool will be in proper position to traverse the form desired, the cam H¹ giving a positive movement to the carriage, as from the position in fig. 1, to that in fig. 3, and returning.

Attached to the carriage G is a transverse guide, L, to which an ordinary slide-rest, M, is attached, the said rest adjustable on the guide L, in the usual manner for slide-rests.

To the carriage a lever, N, is pivoted, at n, passing along over the carriage, its other end provided with an arm, or stud, d, which sets into the groove f, of a guiding-block, P, so that as the carriage is moved from the position in fig. 1, to that in fig. 3, the said lever N will be thrown out or in, as the case may be, or will follow in the form of the groove f, here represented as a single incline, and corresponding to the former D.

The lever N is attached to the slide-rest so as to move it out and in, according to the form indicated by the groove or slot in the block P.

In the slide-rest, the spinning-tool e is fixed in similar manner, as the common turning-tool; consequently the tool being set in the position seen in fig. 1, outside of the disk of metal, and the disk revolving, the tool is moved along by the turning of the shaft H², and guided in the proper path to work the metal down on to the former. The shaft H² being turned by the hand of the operator, regulates the movement of the tool according to the work being produced, the tool, however, by the block P, being automatically guided in a proper path, and for the ease and convenience of the operator, I arrange a counter-shaft, R, with a crank-wheel, S, by which a pinion, T, on the shaft R, works into a gear, U, on the shaft H².

It will be readily seen that different forms may be produced by the same machine, by changing both the former D and block P, the groove in the block P always corresponding to the former D.

The adjustment of the spinning-tool will be readily understood by those skilled in the use of the slide-rest, and needs here no explanation.

I do not wish to be understood as broadly claiming automatically guiding the spinning-tool in a mechanically-defined path, as such I am aware is not new; and I am also aware that machines for spinning have

been produced, in which both the former and spinning-tool have been operated and guided by the same power, but to this there are serious objections, as with one piece of metal it is necessary that the tool be moved slower than with another. It is, therefore, essential that the judgment of the operator may be exercised in guiding the tool, to adapt itself to the peculiarities of the metal, or to the forms into which the metal is to be wrought.

Having fully described my invention,

What I claim as new and useful, and desire to secure by Letters Patent, is—

1. The arrangement of the guide-block P, with the longitudinal carriage G, combined with the lever N,

so as to operate the tool on the transverse guide L, through the shaft H², substantially in the manner herein set forth.

2. The carriage G, and transverse guide L, with the rod I, when the said carriage and guide are made adjustable thereon, substantially as set forth.

3. In combination with the mandrel E, in the head E, the spirally-grooved wheel E⁵, arranged so as to operate the said mandrel, substantially as set forth.

J. J. MARCY.
